UNITED STATES PATENT OFFICE.

BENJAMIN B. PHILLIPS, OF GREENSBORO, NORTH CAROLINA, AND CHARLIE W. EVANS,
OF NORFOLK, VIRGINIA.

EARTH-AUGER.

1,140,607.

Specification of Letters Patent.

Patented May 25, 1915.

Application filed March 5, 1914. Serial No. 822,710.

To all whom it may concern:

Be it known that we, BENJAMIN B. PHILLIPS and CHARLIE W. EVANS, citizens of the United States, residing at Greensboro and

5 Norfolk, respectively, in the counties of Guilford and Norfolk, respectively, and States of North Carolina and Virginia, respectively, have invented certain new and useful Improvements in Earth-Augers, of 10 which the following is a specification.

This invention relates to improvements in earth augers, more particularly to the class employed for forming postholes, and has for one of its objects to improve the construction and increase the efficiency and utility of devices of this character.

Another object of the invention is to provide a device of this character whereby the outer portion of the earth is acted upon in 20 advance of the earth which is located nearer the center of the cavity formed by the auger, whereby the force required is decreased without decreasing the efficiency of the device.

25 Another object of the invention is to provide a simply constructed device in which the boring portion may be disconnected for repairs or renewal of broken parts.

Another object of the invention is to provide 30 a device having independently operative boring members which are adjustable relative to each other.

Another object of the invention is to provide 35 an attachment whereby grass, roots and like growths will be severed and prevented from interfering with the removal of the earth during the boring operations.

With these and other objects in view the invention consists in certain novel features 40 of construction as hereinafter shown and described and then specifically pointed out in the claims; and in the drawings illustrative of the preferred embodiment of the invention Figure 1 is a side elevation of the improved implement. Fig. 2 is a plan view 45 of the boring portion of the implement with the handle or stock in section on the line 2-2 of Fig. 1. Fig. 3 is a detached plan view of the supplemental or smaller boring member. Fig. 4 is a side view of the portion 50 shown in Fig. 3. Fig. 5 is a detached perspective view of the main boring portion of the implement. Fig. 6 is a detached perspective view of the grass root cutting at- 55 tachment.

Corresponding and like parts are referred to in the following description and indicated in all the views of the drawings by the same reference characters.

The improved device comprises a handle 60 or stock 10 provided with a turning head 11 at one end and pointed as represented at 12 at the opposite end, the point designed to penetrate the earth in advance of the boring implement in the usual manner. The 65 stock 10 is preferably threaded and squared at the juncture of the point 12 and the body of the stock and provided with a stop nut 13 at the upper end of the squared portion. The main boring member is represented conventionally at 14 and in S-like form with 70 the terminals increased slightly in width and knife-edged as represented at 15. The terminals are bent downwardly below the general line of the member 14 as represented 75 in Fig. 1. Engaging the stock 10 beneath the body portion of the main boring member 14 is a smaller boring member represented as a whole at 16 with knife-edged terminals 17, the latter being bent downwardly and 80 substantially in transverse alinement with the cutting edges 15 of the main boring implement. The member 16 is less in diameter than the member 14 and will preferably be so located that the cutting edges 15 of the 85 member 14 operate in advance of the cutting edges 17 of the member 16, which thus becomes an auxiliary cutter coacting with and supplemental to the main cutter 14. The members 14-16 have square apertures which 90 engage the correspondingly shaped portion of the stock 10 and are secured in position by a nut 18 which presses the members 14-16 against the stop nut 13.

With an implement thus described, as the 95 stock 10 is rotated the cutting terminals 15 of the main member 14 will form an annular cavity in the ground while the cutting terminal 17 of the inner or supplemental cutting member 16 will sever the core of earth 100 left by the main cutting member, and thus remove all of the earth, the cutting requiring less force than if the cutting portions 15 extended to the center of the member 14. The cutting terminal 17 of the cutting member 105 16 operating rearwardly of the cutting members 15 require less force to operate them, as will be obvious.

Formed in the member 14, preferably in its upper face, are sockets 22 preferably with 110

dovetailed or overhanging sides 19 and converging toward the inner edge of the cutter member to receive and support the correspondingly dovetailed base portions 20 of 5 cutting blades 21. At their outer ends the sockets 22 are formed with recesses or seats to receive the "root" portions of the blades 21. The blade portions are thus directed downwardly with their outer faces flush 10 with the periphery of the member 14, and do not retard the movement of the implement. The blades 21 operate to sever grass roots and like growths or material and prevent them from interfering with the operation 15 of the implement, or preventing the removal of the implement with its load from the ground. The blades 21 with their base portions are readily removable for repairing or sharpening, or to be dispensed with when 20 the implement is employed in soil in which grass roots or like growths are not encountered.

The improved implement is simple in construction, and can be manufactured of any 25 required size or capacity.

Having thus described the invention, what is claimed as new is:—

1. An earth auger comprising a stock, a main member connected to said stock and 30 formed with a plurality of radially disposed cutting portions, and an auxiliary member of less size than the main member and connected to the stock and formed with a plurality of radial cutting portions operating 35 between the stock and the cutting portions

of the main member, the cutting portions of said main member operating in advance of the cutting portions of the auxiliary member.

2. An earth auger comprising a stock, a main member connected to said stock and formed with a plurality of radially disposed cutting portions and with radially directed 40 sockets, and root severing devices each including a base portion seated in one of said 45 sockets and a downwardly directed cutting blade.

3. An earth auger comprising a stock, a main member connected to said stock and formed with a plurality of radially disposed cutting portions and with radially directed 50 sockets, each socket having a recess at its outer end, and root severing devices each including a base portion seated in one of said 55 sockets and a downwardly directed blade engaging in one of said sockets and supported thereby from lateral displacement.

In testimony whereof we affix our signatures in presence of two witnesses.

BENJAMIN B. PHILLIPS. [L.S.]
CHARLIE W. EVANS. [L.S.]
